R. S. Blair

UNITED STATES PATENT OFFICE.

ROBERT S. BLAIR, OF NEW ROCHELLE, NEW YORK.

SHARPENING DEVICE.

1,173,549.

Specification of Letters Patent. Patented Feb. 29, 1916.

Application filed July 13, 1907. Serial No. 383,692.

To all whom it may concern:

Be it known that I, ROBERT S. BLAIR, a citizen of the United States, residing at New Rochelle, in the county of Westchester 5 and State of New York, have invented certain new and useful Improvements in Sharpening Devices, of which the following is a full, clear, and exact description, such as will enable others skilled in the art 10 to which it appertains to make and use the same.

This invention relates to edge tools and more particularly to sharpening devices therefor.

15 One of the objects thereof is to provide simple and efficient devices for sharpening a blade.

Another object is to provide practical means whereby devices of this nature are 20 adapted to perform protective and other functions.

Another object is to provide a convenient and reliable sheath for a blade.

Another object is to provide effective 25 means whereby a sheath or other protective device is adapted to aid in sharpening the blade which it protects.

Other objects will be in part obvious and in part pointed out hereinafter.

30 The invention accordingly consists in the features of construction, combinations of elements and arrangement of parts which will be exemplified in the construction hereinafter set forth, and the scope of the application of which will be indicated in the following claims.

In the accompanying drawings wherein are shown one or more of various possible embodiments of the several features of this 40 invention; Figure 1 is an elevation of a blade within a sheath, the nearer portion of the sheath being removed in order to show the construction more clearly. Fig. 2 is a sectional view taken along the line $x-x$ of Fig. 1 and appearing on a slightly larger scale. Fig. 3 is a side elevation of an ax 45 and devices associated therewith. Fig. 4 is a sectional view taken substantially on the line $y-y$ of Fig. 3 showing a detail of the construction thereof.

50 Similar reference characters refer to similar parts throughout the several views of the drawings.

Referring now to Fig. 3 of the drawings, 55 there is shown an ax comprising the handle

1 and head or blade 2. Pivoted to handle 1, as by the pin 3 upon a flat spring 4, is an arm 5 having rigidly secured thereto a sheath 6. This sheath is adapted to extend both sides of the blade and is provided with 60 linings 7 upon each sheath member between which the blade rests. These linings are provided with abrasive surfaces and are adapted, upon movement with relation to the blade, to grind or abrade the edge portion thereof and sharpen the edge. It may here be noted that the term "abrasive", as used throughout this specification and the following claims, is intended to comprehend 65 any characteristic of a surface whereby a metallic edge portion may be sharpened whether this surface be that of a metallic member, file, steel or the like, or be of the nature of emery or carborundum. These lining members 7, as best shown in Fig. 4 70 of the drawings, are preferably of convex conformation and thus tend to give a hollow ground edge, or if desired they may be of any conformation best adapted to form the particular type of edge desired. Sheath 75 6 is open at the ends as at 8 and is provided with a strap 9, if desired, whereby the same may be rigidly held in a position in which it protects the edge of the blade.

The method of use of this embodiment 80 of my invention is as follows. When it is desired merely to use the ax, strap 9, if the same is employed, is loosened and the sheath swung downwardly into a position substantially parallel with the handle 1. If it is 85 desired to sharpen the ax the pin 3 is snapped out of position permitting the release of the arm 5 and the same may then be rocked as indicated in dotted lines at 10, and rapidly grinds or sharpens the edge. 90 If desired the arm 5, which is provided with a handle portion 11, may be reversed, that is the sheath may be placed upon the ax with the arm 5 extending away from the handle, whereby a freer swing in grinding is permitted. It is to be understood that the blade 95 will ordinarily be sharpened by the mere swinging away of the sheath therefrom in the use of the ax, but the above described method wherein the sheath is released from the ax-handle is somewhat more rapid in 100 its action.

In Fig. 1 is shown a knife-blade 12 within a sheath 13 provided with the abrasive members 14, as perhaps best indicated in Fig. 2 110

of the drawings. In this construction there may be provided, if desired, a flat spring 15 resting against the back of the blade whereby it is thrown into operative relation to 5 the abrasive members. The method of use of this modification should be largely obvious from the above description, and it will be noted that the blade is sharpened by merely being drawn from and re-inserted 10 in the sheath as in the course of ordinary use.

It may here be noted that the term "protect", as used throughout this description and the following claims, is intended as descriptive of a function of any device adapted to tend to prevent the blade from becoming dulled or from accidentally exercising 15 its cutting functions.

It will thus be seen that I have provided 20 a device by which the several objects of this invention are achieved. The sharpening of the blade is not only performed without requiring separate attention, but is quickly and accurately accomplished, the sheath 25 members serving in the embodiment shown as guides in holding the blade in relation to the sharpening elements. Moreover, the sharpening or abrasive elements are protected as from rain and the like and may be 30 readily cleansed. These elements, moreover, aid in holding the sheath members in stiffened relation whereby the blade is more readily thrust between the same.

As many changes could be made in the 35 above construction and many apparently widely different embodiments of this invention could be made without departing from the scope thereof, it is intended that all matter contained in the above description 40 or shown in the accompanying drawings shall be interpreted as illustrative and not in a limiting sense.

Having described my invention, what I 45 claim as new and desire to secure by Letters Patent is:—

1. In a device of the class described, in combination, a sheath comprising means adapted to protect a blade, and abrasive means mounted upon said protecting means 50 adapted to sharpen said blade.

2. In a device of the class described, in combination, a sheath comprising means adapted to protect a blade, and abrasive means mounted upon said protecting means 55 adapted to sharpen said blade, said abrasive means being mounted longitudinally of said sheath and being adapted to stiffen the same.

3. In a device of the class described, in combination, a sheath, and abrasive means 60 mounted upon said sheath adapted upon a blade being drawn lengthwise thereof to sharpen the same.

4. In a device of the class described, in combination, a sheath, and abrasive means 65 mounted upon said sheath adapted upon a

blade being drawn therefrom to sharpen the same, said abrasive means being formed and mounted to embrace the edge of the blade.

5. In a device of the class described, in combination, means extending entirely about a blade and adapted to protect the edge thereof, and abrasive means mounted within the same and adapted to sharpen said edge upon the blade being drawn lengthwise of 75 said first mentioned means.

6. In a device of the class described, in combination, a sheath comprising protective means extending along each side of a blade and connected across the back thereof, and abrasive means mounted within said sheath and adapted to engage opposite sides of the edge of the blade and to tend to sharpen 80 the same upon the blade being drawn lengthwise of the sheath.

7. In a device of the class described, in combination, abrasive means and a sheath adapted to hold said abrasive in operative relation to the edge of a blade to sharpen 85 the same and adapted to receive and protect said blade.

8. In a device of the class described, in combination, abrasive means adapted to engage opposite sides of the edge portion of a blade, and means upon which said abrasive 95 means are mounted adapted to engage the body portion of said blade and guide said edge into operative relation to said abrasive means.

9. In a device of the class described, in combination, abrasive means adapted to contact with a curved edge, and means adapted to rock the same along said edge.

10. In a device of the class described, in combination, a sheath adapted to fit about 105 the edge of an ax-blade and provided with an abrasive lining, and means whereby said sheath may be seized and moved to sharpen said edge.

11. In a device of the class described, in combination, a sheath adapted to fit about the edge of an ax-blade, means connecting said sheath with the handle of the ax and adapted to permit the same to swing away therefrom, and an abrasive lining in said 115 sheath adapted to engage and sharpen the edge of the ax.

12. In ax construction, in combination, a handle upon which the head of the ax is mounted, a sheath adapted to engage and 120 protect the edge of said ax-head, and means connected with said sheath and pivotally connected with said handle, said pivotal connection comprising a spring-pressed pivot pin adapted to permit the swinging 125 of said sheath about the same and the disconnection of said connecting means.

13. In ax construction, in combination, an ax-handle, a sheath fitting about the edge of the head of the ax, means connected 130

with said sheath and pivotally and detachably connected with said handle and adapted to permit the sheath to be swung away from said edge, and an abrasive lining 5 within said sheath adapted to engage said edge and sharpen the same upon being moved with relation thereto.

14. A sheath adapted to protect a blade and abrasive means mounted within and

protected by said sheath and adapted to sharpen said blade.

In testimony whereof I affix my signature, in the presence of two witnesses.

ROBERT S. BLAIR.
